UNITED STATES PATENT OFFICE

GODFREY A. MUELLER, OF POINT PLACE, OHIO, ASSIGNOR TO THE DE VILBISS COMPANY, OF TOLEDO, OHIO, A CORPORATION OF OHIO

SPRAY HEAD

Application filed March 14, 1927. Serial No. 175,126.

This invention relates to spraying devices, and particularly to a spray-head for spray-guns, or the like, used more particularly for the application of paint and other surface coating materials in both round and flattened or fan stream form.

The object of the invention is the provision in a device of this character of simple and efficient means, other than the nozzle members of the spray-head, which is manually operable to open or close the supplemental jets from which the stream flattening air discharges.

The invention is fully described in the following specification and two embodiments thereof illustrated in the accompanying drawings, in which,

Figure 1 is a central longitudinal sectional view of a spray-head embodying the invention with the valve member partly broken away. Fig. 2 is a front end elevation thereof. Fig. 3 is a side elevation of slightly modified form of spray-head with a portion in central longitudinal section and with the valve member disposed interiorly of the outer nozzle. Fig. 4 is a front end elevation thereof, and Fig. 5 is a cross-section on the line 5—5 in Fig. 3.

Referring particularly to Figs. 1 and 2 of the drawings, 1 designates the inner nozzle of spray-head embodying the invention and 2 the outer nozzle. The inner nozzle, in the present instance, has its forward end reduced and terminating in a small nipple 3 having a restricted axially disposed discharge orifice 4 therethrough, which communicates through the hollow interior of the nozzle member 1 with a source of supply of the material to be sprayed. The rear end portion of the nozzle 1 has an enlargement 5 adapted to be threaded at its rear end into a gun or holder body, or secured thereto in any other suitable manner, as well understood in the art. The forward end of the enlargement 5 is shown as terminating at the rear of the nozzle end in an annular forwardly facing shoulder forming an undercut or inner conical seating face 6, against which the rear end of the outer nozzle 2 is adapted to seat and to which it may be releasably held by a union nut 7.

The outer nozzle 2 is hollow or bored out to encircle the nozzle 1 in advance of its enlargement 5 to form an air space 8 therebetween in communication through passages 9 in said enlargement with a suitably controlled air supply, as well understood in the art. The bore of the outer nozzle is reduced at its forward end to form a restricted main air discharge orifice 10, which receives the nipple 3 of the inner nozzle and forms an annular discharge passage therearound.

The nozzle 2 is provided at its forward end with a pair of forwardly projecting bosses 11, one at each of opposite sides of the orifice 10 in transversely spaced relation thereto and each having its inner side forming arcuate faces 12 of a common circle, concentric to the nozzle orifices 4 and 10, or substantially so. Each boss has a supplemental air discharge orifice 13 extending therethrough with its rear end in communication with the air space 8 of the spray-head and with its outer end opening through the arcuate face 12 of the boss and directed toward the axis line of the nozzles, so that air discharged from the two supplemental passages 13 will meet at a point on said axial line, which is outwardly spaced a predetermined extent from the main discharge orifices of the nozzles, thereby effecting a flattening of the main material laden air stream, as well understood in the art.

In order to control the discharge of air from the supplemental discharge passages 13, a ring valve 14 is mounted between the bosses 11 in complimentary seating engagement with the inner arcuate faces 12 thereof and for turning movements relative thereto. This valve has diametrically opposed tapering portions 15, which, when the valve is in one position of its turning movement, completely close the discharge ends of the passages 13, and when turned in one direction from such position, effect a gradual opening of the passages to full open position, thus enabling the passages to be fully or partially opened, as desired, for operating purposes. The tapered portions 15 of the valve terminate abruptly at one end in inwardly extending shoulders so that the passages 13 may be quickly opened to full extent by turning the valve in a direc-

tion for the abrupt ends of the tapered portions to pass from over the same. The valve 14 is exposed at opposite sides of the nozzles, at the spaces between the bosses 11, to facilitate a grasping and turning of the same by the operator.

While the valve 14 is shown in connection with a particular form of spray-head, it will be understood that the use of the invention 10 is not confined to any particular form or type of spray-head, so long as it may have provision for the mounting of the valve 14, or one of similar type, between the discharge ends of the supplemental air discharge 15 passages.

In Figs. 3, 4 and 5 the invention is modified to show the ring valve as mounted within the outer nozzle member instead of without the same, as in Figs. 1 and 2. In this form 20 of the invention, 20 and 21 designate the inner and outer nozzle members, respectively, with the air-space 22 therebetween slightly enlarged over that shown in Fig. 1 to facilitate the mounting of the ring valve 23 within 25 in said space. This ring valve, in the present instance, is shown as having a conical seat against the inner surface of the outer nozzle in closing relation to the inner ends of the supplemental air discharge passages 24 30 and having openings 25 therethrough adapted to be placed into or out of register with the inner ends of the passages 24 by a turning of the valve as is apparent. A stem 26 projects radially from the valve member 35 through a side opening 27 in the outer nozzle 21 to facilitate a manual turning of the valve from without the nozzle.

It is evident that in both illustrative embodiments of the invention a unitary valve 40 member for controlling both supplemental air discharge passages is employed; that said valve member is separate from both nozzles of the spray-head, and that it is removable relative thereto to effect an opening, closing 45 or regulation of the supplemental air jets from without the spray-head and without effecting the adjustment of one nozzle relative to the other, while such nozzles, at the same time, are capable of relative rotary adjustment to place the supplemental discharge jets 50 in any position around the spray axis, as may be desired to flatten the main or material laden stream in a horizontal, vertical or other plane to suit the work being performed.

55 I wish it understood that the invention is not limited to any particular construction, arrangement or form of the parts, as it is capable of numerous modifications and changes without departing from the spirit 60 of the claims.

Having thus described my invention, what I claim as new and desire to secure by Letters Patent is:

1. In a spray-head, an outer air discharge 65 nozzle having a main central air discharge

orifice and having diametrically opposed bosses at its forward end equidistantly spaced from said main orifice and each having an arcuate inner face concentric to the main orifice and forming segments of a common circle, each of said bosses also having a supplemental air discharge orifice opening through its conical face, and a ring valve disposed between and fitting said arcuate faces and operable to simultaneously open or close said supplemental passages.

2. In a spray-head, inner and outer discharge nozzles cooperating to form a main air discharge orifice and having a space therebetween in communication with a source of air pressure supply, said nozzles being relatively rotatable and said outer nozzle having supplemental air discharge passages, and a single valve associated with the outer nozzle and operable to open or close said supplemental passages in any position of relative adjustment of the nozzles.

3. In a spray-head, inner and outer nozzles cooperating to form a main air discharge orifice having communication with a source of air pressure supply, said nozzles being relatively rotatable and the outer nozzle having a pair of opposed supplemental air discharge passages in communication when the air pressure source and a single ring type of valve associated with said supplemental passages and operable to simultaneously adjustably control the discharge of air from the supplemental passages by rotary movements of the valve relative to the outer nozzle, the axis of adjustment of said valve being longitudinal with respect to the axis of said main air discharge orifice.

In testimony whereof I have hereunto signed my name to this specification.

GODFREY A. MUELLER.

CERTIFICATE OF CORRECTION.

Patent No. 1,731,497.

Granted October 15, 1929, to

GODFREY A. MUELLER.

It is hereby certified that error appears in the printed specification of the above numbered patent requiring correction as follows: Page 2, line 94, claim 3, for the word "when" read "with"; and that the said Letters Patent should be read with this correction therein that the same may conform to the record of the case in the Patent Office.

Signed and sealed this 26th day of November, A. D. 1929.

(Seal)
